UNITED STATES PATENT OFFICE.

EARL E. McGREW, OF LINCOLN, NEBRASKA, ASSIGNOR TO McGREW MACHINE COMPANY, OF LINCOLN, NEBRASKA, A CORPORATION OF NEBRASKA.

FOLDING CAMP CHAIR.

Application filed September 2, 1924. Serial No. 735,514.

To all whom it may concern:

Be it known that I, EARL E. McGREW, a citizen of the United States, residing at Lincoln, in the county of Lancaster and 5 State of Nebraska, have invented certain new and useful Improvements in Folding Camp Chairs, of which the following is a specification.

My invention relates to folding chairs. 10 Such chairs are most commonly demanded for use on automobile and other camping trips, and my chair has been designed primarily for this purpose. To meet this need the chair must be strong, rigid and 15 comfortable when set up and it must fold into a very compact bundle. The folding and unfolding must be accomplished in the minimum of time and must be as nearly automatic as it is possible to make it. It 20 must have no loose parts which are liable to become lost when breaking camp. My invention has for its object the provision of such a chair. Other objects will be brought out in the following description.

25 Referring now to the drawings,

Figure 1 is a perspective view of one form of my chair as viewed when set up.

Figure 2 is a view in perspective of the lower portion of one of the back supports.

30 Figure 3 is a perspective view of the latch for locking the back support.

Figure 4 is a rear elevation of one of the back supports with its latching connections, showing also the directions in which the 35 various latching forces act.

Figure 5 is a view in perspective of a portion of a chair which is equipped with a modified form of latch.

40 Figure 6 is a perspective view from the rear of one of the corners of the chair shown in Figure 5.

The stool portion of my chair is shown in Figure 1. The foot portion of the stool comprises two U-shaped members 10 of strap iron, the members 10 being pivotally connected by the rod 11. Pivotally connected to the rod 11 at each end thereof are two links 12. The free ends of the front and rear links 12 of each lateral pair are pivotally secured to a rod 13, the pair of rods 13 being the support for the seat 14 which is preferably made from canvas or similar fabric. The front and rear links 12 of each lateral pair are also connected by a bail 15, the ends of which are pivotally secured in

the links 12 adjacent their outer extremities. The inner portions of the bails are provided with loops which are made by bending when forming the bails. The links 16 are each secured at one end in a loop of a bail 15 60 and at the other end in the side portion of one of the U-shaped members 10. The U-shaped members 10 are detachably connected with each other by means of the latching links 17, each of which is pivotally and permanently secured to a member 10. The free ends of the links 17 are each provided with a plurality of notches for engaging a pin projecting from the opposite member 10. 70

The stool alone as above described is old and I lay no claim to any novel features thereof, except as they cooperate in structure and operation with the chair back and its various parts. The stool however is remarkable for its simplicity and rigidity and for the ease with which it may be folded and unfolded. By unlatching the links 17 the stool may be almost instantly folded into a bundle having dimensions only slightly 80 in excess of those of the U-shaped member 10. It may be as quickly set up, the seat being made taut by forcing the free ends of the U-shaped members toward each other and then held taut by latching the links 17. 85

The only drawback to the stool is that it has heretofore been impossible to convert it into a chair and to at the same time retain all of its advantages as a foldable article of furniture. The stool requires a back rest 90 which is rigid and secure and which may be folded with the stool. For this purpose I have provided two supporting arms 18 for supporting the fabric back 19, with a latching device 20 for the supporting arms. I 95 will now describe these in detail.

The latching device 20 has an aperture 21 for pivotally securing it to a rod 13 at the rear extremity thereof, the rods 13 being that part of the stool which supports the 100 seat 14. Integral with the latch and projecting rearwardly therefrom are two wings 22 and 23, the wing 22 being crimped inwardly at its lower extremity as shown in Figure 3. The back wall of the latch 20 105 is cut away at its upper end, leaving upwardly projecting ears on the wings 22 and 23. The ears are apertured at 24. The wings 22 and 23 are cut away appreciably below the pivot aperture 21 and the back portion 110

of the clamping member 20 projects downwardly and laterally and is provided with an arcuate slot 25 which is concentric with the aperture 21. The latches 20 are made in rights and lefts but otherwise they are identical. They are secured to the respective rods 13 with the wings 22 and 23 projecting rearwardly and with the arcuate lower ends projecting inwardly with respect to the chair.

The supporting rods 18 are made from angle channel iron having an external width equal to the distance between the ears at the upper ends of the wings 22 and 23. The rods 18 are rounded in their upper portions to afford smooth surfaces for the fabric back 19. At the lower extremity of each rod 18, one wall of the channel iron is crimped inwardly at 26, corresponding to the crimp 22' of the latch 20. The supporting rods 18 are also made in rights and lefts, but only with respect to the crimp 26. Apertures 27 are formed in the walls of the channel iron supporting rods 18.

The supporting rods 18 are connected with their latches 20 by means of pivot pins 28 passing through the aligning apertures 24 and 27 and the fabric back rest 19 is then placed in position on the pair of supporting rods 18. The lower portion of the latching member 20 serves as an abutment for the lower extremity of the supporting rod 18 to prevent rearward tilting of the supporting rod. When the latch is not functioning, the supporting rods 18 are free to tilt and to fall forwardly.

I will now describe the operation of the latch. The channeled portion of the latching member 20 is slightly wider at the bottom than it is at the top. While the channeled portion of the latch is just wide enough at the top to accommodate the supporting rod 18, it is wide enough at the bottom to permit slight lateral play. The latching member 20 is pivoted to the rod 13 but its pivotal movements are limited by the pin 29 secured to the link 12 and passing through the arcuate slot 25. When the latch 20 is not functioning, the arm 18 is free to move on its pivot 28 so that the lower extremity of the arm can easily move into or out of the channeled portion of the latch. The chair is held inverted while it is being set up, so that the extremities of the arms 18 seat themselves in the channeled portions of the latches 20. As the movement of the various parts progresses toward the position shown in the drawings, the latch member 20 moves until the pin 29 is seated in the inner extremity of the slot 25, but at the same time there is an outward lateral movement of the arm 18 in the direction of the arrow A (Figure 4). This lateral movement is stopped when the back rest 19 becomes taut. The tension of the back rest 19 is inward

on the arms 18, and since these arms are pivoted the tendency of the upper ends of the arms 18 is to move in the direction of the arrow B. This however causes the opposite ends of the arms 18 to move in the direction of the arrow C, thus forcing the crimped portion 26 under the crimped portion 22' and holding it there under the tension of the back rest 18. The supporting arms 18 are therefore held rigidly against all movement. The tension of the back rest prevents spreading of the upper portions of the supporting arms. The pin 29 in the extremity of the slot 25 prevents the arms from converging. Forward tilting movement of the arms is prevented by the latch. Rearward tilting of the arms is prevented by the abutments for the lower ends of the arms.

In Figure 5 I show a brace which may be used either with or without the abutment for preventing the rearward tilting movement of the arms 18. The side members 30 are made from strap iron which is bent inwardly at each end as shown. The bent ends are provided with apertures for receiving the rods 13 whereby the side members are secured at both their front and rear ends to the rods 13, the parts being held in their assembled relation by the nuts 31 on the front ends of the rods 13. The braces are each in the form of a pair of pivoted links, their outer ends being pivotally secured to the side members 30 and to the arms 18' as shown in Figure 5. This construction permits the automatic folding of the halves of the links 32 on each other when the chair is being folded, the links 32 resuming their operative positions during the setting up of the chair. It is to be understood however that the link arrangement 32 and the side members 30 are not modifications since these elements may be added to the structure shown in Figure 1.

In Figures 5 and 6 I show a modified form of the structure for latching the chair-back in its set up position. In this case the back supporting arm 18' is pivoted between the two wings 22' and 23' of the latching device 20', this relation being the same as that of the corresponding parts by Figure 1. The latching device 20' is provided with a downwardly projecting tongue 33 which has a link 34 pivoted thereto. The link 34 is provided with a slot 25' which is analogous to the slot 25 in the Figure 1 construction, and it is slidably engaged by the headed pin 29', secured to the link 12 of the stool. The function of the various parts and the operation of the chair as a whole is almost identical whether the preferred or the modified form of latch is employed.

My invention thus provides a back rest for stools or in other words converts such stools into chairs with all of the added com-

fort of chairs over stools. The stool itself is of a type which can be compactly folded into the minimum of space and which is exceedingly light in weight, but the addition of my back rest to the stool adds almost nothing to the weight of the chair or to the dimensions of the folded bundle. The stool is of course locked against any possibility of accidentally collapsing and my chair back is so designed that it is latched and unlatched automatically with the latching and unlatching of the stool. The latch moreover is positive in action, and it prevents both the forward tilting of the back and the inward movement of the supporting arms for the back. The supporting arms, being made from channel steel, are exceedingly rigid and will not bend even under the roughest usage. Their abutments are somewhat remote from their pivots so that the supporting arms are provided with rigid pivotal connections which prevent the rearward collapsing of the back rest when the occupant leans back heavily. The structure of the latch is such that the latch alone is sufficient for this purpose but if it is felt that additional reinforcement is desirable or necessary, the link braces of Figure 5 may be added without materially increasing the weight, bulk, or cost of the chair.

Having thus described my invention in terms which will be readily understood by others skilled in the art to which it pertains, what I claim as new and desire to secure by Letters Patent of the United States is:—

1. A foldable back rest for chairs, said back rest including a pair of supports secured to the chair at its rear corners, each of said supports being provided at its joint with the chair with a pair of horizontally positioned pivots, one of said pivots being in alignment with the side edge of the chair seat and the other of said pivots being rearward of and parallel to the rear edge of the chair seat.

2. In combination with the side member of the seat of a folding chair, a latch member pivotally secured to said side member at its rear extremity and having said side member as its axis for pivotal movement, a back rest support, and a horizontal transverse pivot pin connecting said back rest support to said latch member.

3. In combination with the side member of the seat of a folding chair, a latch member pivotally secured to said side member at its rear extremity and having said side member as its axis for pivotal movement, means for limiting the pivotal movement of said latch member, a back rest support, and a horizontal transverse pivot pin connecting said back rest support to said latch member, said pivot pin being positioned above said side member.

4. In combination with the side members

of the seat of a foldable stool, said side members each having a latch member secured thereto at its rear extremity by means of a forwardly and rearwardly extending pivot, means for limiting the inward pivotal movements of said latch members, each of said latch members having secured thereto a back rest support by means of aligning pivots which are positioned transversely with respect to the stool, a flexible back rest connecting the upper portions of said back rest supports, and means including said back rest for latching said back rest supports in said latching members when the stool is in its set up position.

5. In a foldable chair, a latch member and a connection for securing said latch member to the chair at one of the rear corners thereof, said connection comprising a forwardly and rearwardly extending pivot, said latch member being channeled and having its side walls directed rearwardly, one of said side walls being turned inwardly to form a lip at one of the extremities of said latch member, a back rest support within said channeled member and secured thereto by a transverse pivot passing through the rearwardly extending walls of said latch member and affording sufficient play for said back rest support to engage said lip to maintain said back rest support and said latch in substantial alignment.

6. In combination with a foldable stool having a fabric seat which is secured at its opposite sides to frame side pieces which are movable toward each other when folding the stool, each of the side pieces having a support secured thereto at its rear extremity, each of said supports being secured to its respective side piece by a pair of horizontal pivots which extend in directions at right angles to each other.

7. In combination with a chair seat having side members which are foldable toward each other, each of said side members having a latching device secured thereto at its rear extremity, said latching devices being each in channeled form and having an in-turned lip in the lower portion of its outer wall, each of said latching devices having the lower portion of a back rest support within the channeled portion thereof, said back rest support being connected to its latching device by means of a horizontal transverse pivot which is spaced from the lower extremity of said support, and a tension back rest connecting the upper portions of said back rest supports, said back rest being under tension when said side members of the seat and said back rest supports are in their operative positions, the tension of said back rest tending to spread apart the lower extremities of said back rest supports and causing them to engage said in-turned lips to hold said back rest supports

in substantial alignment with said latching members.

8. In combination with a chair seat having side members which are foldable toward each other, means for rigidly securing said side members in spaced apart relation, each of said side members having a latch member secured thereto at its rear extremity, each of said latch members having a back rest support secured thereto by means of a horizontal transverse pivot which is spaced above its respective side member so that each of said back rest supports may be folded into parallel relation with its side member,

a flexible back rest secured between and to the upper portions of said back rest supports, said back rest being under tension when said side members of the seat are in their spaced apart relation, and means whereby the tensioning of said back rest causes the lower extremities of said back rest supports to be engaged by said latch members to prevent the folding of said back rest supports.

In testimony whereof I affix my signature.

EARL E. McGREW.
